United States Patent

Des. 239,689

Patented Apr. 27, 1976

239,689

CUTTING BOARD

Donald W. Doman, Janesville, and Gerald A. Rau, Baraboo, Wis., assignors to Flambeau Products Corporation

Filed Apr. 1, 1974, Ser. No. 456,953

Term of patent 14 years

Int. Cl. D7—04

U.S. Cl. D7—46

FIG. 1.

FIG. 2.

FIG. 3.

FIG. 4.

FIG. 5.

FIG. 1 is a top view of a cutting board showing our new design;

FIG. 2 is a bottom view thereof;

FIG. 3 is a side view thereof, the other side view being substantially identical;

FIG. 4 is one end view thereof, the other end view being substantially identical; and

FIG. 5 is an enlarged cross-sectional view taken along line 5—5 in FIG. 1, a portion thereof being broken away for convenience of illustration.

We claim:

The ornamental design for a cutting board, as shown and described.
